(No Model.)

E. A. EDWARDS.

ELECTRIC LIGHT.

No. 257,678.

Patented May 9, 1882.

UNITED STATES PATENT OFFICE.

EDGAR A. EDWARDS, OF CINCINNATI, OHIO.

ELECTRIC LIGHT.

SPECIFICATION forming part of Letters Patent No. 257,678, dated May 9, 1882.

Application filed September 12, 1881. (No model.)

To all whom it may concern:

Be it known that I, EDGAR A. EDWARDS, a citizen of the United States, and a resident of Cincinnati, in the county of Hamilton and State of Ohio, have invented certain new and useful Improvements in Electric Lights, of which the following is a specification.

The object of my invention is to provide improved means for regulating electric lamps by the counteracting forces of two coils of different resistance, through which the electric current is made to pass in the manner hereinafter described, so that when, by a too great separation of the carbons, the current is reduced the electro-magnet of greater resistance is brought into action, so as to bring the carbons together again.

The various features of my invention will be more fully set forth in the description of the accompanying drawings.

Figure 1 is a front elevation of an electric lamp embodying my invention. Fig. 2 is a perspective view of the electro-magnets and devices for automatically adjusting the regulating-rod or upper-carbon holder, the said rod being shown broken off at top and bottom. Fig. 3 is a sectional plan on the line *xx*, Fig. 2. Fig. 4 is a broken sectional elevation, showing a modified form of Fig. 3. Fig. 5 is a vertical central section of Fig. 2 and the case in which it is inclosed. Fig. 6 is a rear elevation of a broken upper section of my invention, showing the switch for bringing the lamp and its magnet in and out of circuit, the upper right-hand binding-post being shown in section. Fig. 7 is a modified form of clutch-brake.

The lamp here shown is designed to be one of a series placed in a circuit, its construction being such that the operation, adjustment, and shutting out of one lamp will not interfere with the remaining lamp in circuit.

A represents a metallic case, within which the magnets and regulating devices are placed, and it is made of soft iron. *a a'* represent cross-arms attached to the sides of case *A*.

B B' represent vertical rods attached to cross-arms *a a'*.

B'' represents a cross-arm attached to rods *B B'*, forming the base of the lamp.

b represents the lower-carbon holder.

b' represents a set-screw for vertically adjusting the carbon-holder *b*.

Rod *B'* is insulated from metallic connection with the arms *a'* and *B''* by means of gutta-percha or other suitable insulations. Rod *B* is in metallic contact with arms *B''*, and forms a part of the circuit when the lamp is in operation. Rod *B* is insulated from metallic connection with arm *a* by means of gutta-percha washers and bushing; but it has a metallic connection with the binding-post *N* by means of a screw-rod, *D*, as shown in Fig. 6, *c' c'* representing the insulating washers or bushing.

E E refer to an ordinary **U**-shaped electro-magnet, which is composed of two helical coils of coarse wire wound upon spools that are secured to and in metallic connection with the soft-iron case *A*, the wire composing the said coils extending from one to the other, as shown in Fig. 2. One end of the said magnet-wires is connected to switch *F* and the other end to case *A*. *G G* and *G' G'* represent axial armatures.

H H refer to an ordinary **U**-shaped electro-magnet, the two coils of which are composed of wire that is finer than the wire of the upper **U**-magnet, *E E*. The spools of the **U**-magnet *H H* are secured to the soft iron casing *A*, so that in effect these magnets constitute a double **U**-magnet comprising coils of different resistance, those of the fine wire being of greater resistance than those of coarser wire. The magnet *H H* is designed to have a resistance in a circuit equal to that of the dynamic machine and the main circuit of all the lamps, including the coils of the electro-magnet *E*.

h represents dash-pots, in which the lower ends of armatures *G* are placed. Any form of dash-pot may be used.

e h' represent the positive ends of wires of the magnets *E H*. They are electrically connected and united by means of a metallic connection, *p*, to the positive binding-post *P*. The opposite end of the fine magnet-wire *h'* is electrically connected to binding-post *N*, so that when switch *F* is in the vertical position the magnet *E* is in circuit; but when switch *F* is turned and brought in contact with *i* the lamp is short-circuited by cutting the carbons out. Armatures *G G* form the axial cores for magnet *E E*, and *G' G'* are the axial cores for magnet *H H*.

Y represents a yoke which unites the two armatures *G G* and *G' G'*. Through the cen-

ter of yoke Y is a slot or mortise, through which loosely passes the upper-carbon-rod holder L. This rod may be of an H shape, as shown in Fig. 4, or of a hollow square form, 5 as shown in Figs. 2, 3, and 5, or of any other form adapted to an inside two-pointed clutch.

l' represents pivoted levers, the free ends of which rest in stirrups l, the other ends working on pivot l'', attached to one of the spools 10 of the electro-magnet H.

M represents a yoke-lever surrounding the rod L, and provided with cross-head m, resting on the levers l', the opposite end being supported upon the opposite spool of the magnet H. 15

O indicates the friction-clutch brake, which will be made of a thin plate, having knife-edge points adapted to engage the inner walls of the hollow upper-carbon holder, as herein- 20 after set forth. It is placed in the channel of the hollow rod L and rigidly attached to yoke-lever M. As the armature-yoke Y raises stirrups l the pivoted levers l' will also rise, which in turn raise one end of the lever M, and there- 25 by press the sharp edges of clutch O against the side of the rod L, thus raising rod L corresponding to the movements of yoke Y, and a corresponding descending movement of the yoke Y tends to release the ends of clutch O, 30 which allows the descent of rod L, the points of the clutch acting as a brake and checking the rapid motion of rod L.

T represents a retractile armature-spring, one end of which is attached to the armature- 35 yoke Y and the other end to case A.

There are two circuits in my lamp, one of which is the lamp-circuit, which conveys the current to support combustion and form the light, and is as follows: P represents the positive binding-post; p, a metallic wire connection connecting it with the wires e h', which form branches of a divided circuit. The coarse-wire magnet is in the lamp-circuit, and through this magnet the electricity passes to case A, thence 40 through wire Q, through the carbon-holder L, thence through the carbons S S, the carbon-holder b, through arms B'', rod B, and by means of screw-rod D to the negative post N, thence to other lamps in the circuit. The external current, which, in combination with the primary current and magnets, automatically adjusts the 45 one carbon to and from the other and maintains the arc of uniform size, is as follows: The positive current is conveyed by wire h', through magnet H H, and by metallic connection of wire h', thence through wire n, to binding-post N, where it again unites with the lamp current or circuit.

j represents an adjustable stop. It is preferably made of U shape and of soft brass, so as to be bent up or down; but a screw-stop may be used instead. This stop is adjusted so as to prevent the upper carbon from rising high enough to break the arc. 60

65 The following is the mode of operation of my lamp and automatic carbon-adjusting devices. The lamp is adjusted ready for opera-

tion. The two carbons are in contact, the upper one resting freely upon the lower one, and the circuit established by means of switch F. The 70 electricity passes through the lamp in two circuits, as above described, the maximum force being exerted in the lamp-circuit, a minimum amount through the lesser circuit in proportion to the resistances between the entire lamp-circuits and the resistance in electro-magnet H H, which, being of fine-wire coils, has a greater resistance than the electro-magnet of coarse wire. By reason of the greater amount of magnetism developed in the magnet E E, the 80 axial armatures G G are attracted upward into the cavities of the spools of magnet E E, carrying upward the yoke-armature Y, with depending stirrup l and lower axial cores, G' G', thereby elevating the ends of levers l' l'' and 85 carrying upward the cross-heads m of the yoke-lever M and throwing brake-clutch O into contact with rod L, which rod it clutches by angular impingement and carries upward until the ends of lever M come in contact with 90 adjustable stop j, thereby separating the upper and lower carbons and producing the voltaic arc between the carbons. When the carbon wastes away by the action of the current the resistance of the lamp-circuit is increased, 95 magnetism in the electro-magnet E E is decreased, and more current passes through the electro-magnet H H, increasing its magnetism and drawing downward cores G' G', with yoke-lever connections, and clutch O, thus carrying 100 down rod L, and thereby adjusting the carbons and decreasing the resistance of the principal circuit, and also shortening the arc and increasing magnetism in the magnet E E when the downward movement of the carbon-holder 105 is arrested. This movement is continued until the end of lever M touches the top of one of the spools of the electro-magnet H, when the angular impingement of clutch is decreased, 110 allowing rod L to be again raised.

In practice the action of the two magnets of different resistances operating upon the adjusting mechanism is so sensitive and instantaneous in its action that practically the carbons are balanced by the two forces, so as to 115 maintain almost a uniform arc without any perceptible flicker, giving a clear, bright, and desirable light.

When the form of carbon rod L shown in Fig. 4 is employed two clutches O may be 120 employed, one clutch working in each of the respective channels, being rigidly connected to yoke-lever, as above described.

It is obvious that the adjusting mechanism and the arrangement of the electro-magnets of 125 different resistances may be applied by reversing their position so as to adjust the lower instead of the upper carbon holder; or both upper and lower adjustments may be employed in one and the same lamp.

It is also obvious that, instead of yoke Y being made of a single piece of soft iron, two yokes or uniting-arms may be employed, provided one or both be connected to the clutch.

ing mechanism. Such a change would be a mere modification of the first feature of my invention.

What I claim is—

- 5 1. The combination, in an electric lamp, of the channelled carbon-holder with the knife-edged friction-clutch arranged to work in the channel of the carbon-holder and connected to a vibratory yoke, the yoke rigidly connecting the axial cores of the magnets, and adapted to raise said vibratory yoke, whereby the raising of such yoke will cause the friction-clutch to act as a brake for retarding the descent of the carbon-holder, substantially as described.
- 15 2. The combination, with the double **U**-shaped electro-magnet composing magnets of different resistances, of the double-edged friction knife clutch and brake adapted to impinge simultaneously against the opposite sides of the channel-shaped carbon-holder, and mechanism for operating said clutch, substantially as set forth.
- 25 3. In combination with the channel-shaped carbon-holder and the friction-clutch brake, the link-levers *l* *M* and the armature-yoke *Y*, connected with the stirrup *l*, whereby the carbon-holder will rise and fall and adjust the arc of the light, substantially as described.
- 30 4. The soft-iron case *A*, inclosing the two **U**-shaped electro-magnets of different resistance magnetically connected to the interior of the case, in combination with a carbon-holder passing vertically up through the case, and the automatically-operating devices for connecting

the armature-yoke with the carbon-holder, 35 substantially as herein set forth.

5. An electric lamp comprising the soft-iron case *A* and the two **U**-shaped electro-magnets of different resistances magnetically connected to and located within the interior of the case, 40 said magnets having rising and falling axial cores united by a common armature-yoke, with an automatically-adjusting clutch mechanism adapted to raise and lower a metallic carbon-holder passing loosely up through the case, 45 substantially as herein set forth.

6. In an electric lamp, the double **U**-magnet comprising coils of different resistance, with rising and falling axial cores united by a common armature-yoke, the rise and fall of which 50 armature-yoke and cores operate the adjusting clutch mechanism for adjusting the arc of the light, the electro-magnets being magnetically connected to the metallic shell of the case, which acts as a metallic conductor and forms 55 a part of the lamp-circuit through the carbon-holder and carbons, an external circuit being employed for regulating the magnetic forces actuating the common yoke of the two magnets, substantially as set forth. 60

In testimony whereof I have hereunto set my hand in the presence of two subscribing witnesses.

EDGAR A. EDWARDS.
